Primary Examiner — Catherine S Posthauer(74) *Attorney, Agent, or Firm* — Knobbe, Martens, Olson & Bear, LLP(57) **CLAIM**

The ornamental design for a surgical procedure pack as shown and described.

DESCRIPTION

FIG. 1 is a top view of a surgical procedure pack showing our new design in a flat, unfolded configuration; FIG. 2 is a bottom view thereof; FIG. 3 is a front side view thereof; FIG. 4 is a rear side view thereof; FIG. 5 is a left side view thereof; FIG. 6 is a right side view thereof; FIG. 7 is a top perspective view of the surgical procedure pack in an alternate folded position; FIG. 8 is top perspective view of the surgical procedure pack in another alternate folded position; FIG. 9 is a right side view of FIG. 7, the left side view being a mirror image thereof; and, FIG. 10 is a right side view of FIG. 8, the left side view being a mirror image thereof.

The dash-dash broken lines illustrate portions of the surgical procedure pack that form no part of the claimed design. The dot-dot-dash lines are shown for the purpose of illustrating perforated fold lines which form no part of the claimed design.

1 Claim, 7 Drawing Sheets(56)
